CLAIM

The ornamental design for a lid for containers, as shown and described.

DESCRIPTION

FIG. 1 is a perspective view of a lid for containers of a first embodiment;

FIG. 2 is a left side elevation view thereof;

FIG. 3 is a right side elevation view thereof;

FIG. 4 is a front elevation view thereof;

FIG. 5 is a rear elevation view thereof;

FIG. 6 is a top plan view thereof;

FIG. 7 is a bottom plan view thereof;

FIG. 8 is a perspective view of a lid for containers of a second embodiment;

FIG. 9 is a left side elevation view thereof;

FIG. 10 is a right side elevation view thereof;

FIG. 11 is a front elevation view thereof;

FIG. 12 is a rear elevation view thereof;

FIG. 13 is a top plan view thereof;

FIG. 14 is a bottom plan view thereof;

FIG. 15 is a perspective view of a lid for containers of a third embodiment;

FIG. 16 is a left side elevation view thereof;

FIG. 17 is a right side elevation view thereof;

FIG. 18 is a front elevation view thereof;

(Continued)

FIG. 19 is a rear elevation view thereof;
 FIG. 20 is a top plan view thereof;
 FIG. 21 is a bottom plan view thereof;
 FIG. 22 is a perspective view of a lid for containers of a fourth embodiment;
 FIG. 23 is a left side elevation view thereof;
 FIG. 24 is a right side elevation view thereof;
 FIG. 25 is a front elevation view thereof;
 FIG. 26 is a rear elevation view thereof;
 FIG. 27 is a top plan view thereof; and,
 FIG. 28 is a bottom plan view thereof.
